UNITED STATES PATENT OFFICE.

NICOLAUS AUGUST OTTO, OF COLOGNE-ON-THE-RHINE, ASSIGNOR TO THE GAS-MOTOREN-FABRIK-DEUTZ, OF DEUTZ-ON-THE-RHINE, GERMANY.

GAS-MOTOR ENGINE.

SPECIFICATION forming part of Letters Patent No. 350,077, dated September 28, 1886.

Application filed May 27, 1886. Serial No. 203,421. (No model.) Patented in England April 28, 1886, No. 5,804, and in Belgium May 13, 1886, No. 73,097.

To all whom it may concern:

Be it known that I, NICOLAUS AUGUST OTTO, a citizen of Prussia, residing at Cologne-on-the-Rhine, in the Empire of Germany, have invented a new and useful Improvement in Gas-Motor Engines, (for which I have obtained a patent in Belgium No. 73,097, dated May 13, 1886, and have made application for patent in Great Britain, No. 5,804, dated April 28, 1886,) 10 of which the following is a specification.

This invention relates to an improved construction of gas-motor engines, wherein a single-acting working-cylinder is combined with a pump for compressing the air-supply and 15 pump for compressing the gas-supply in such manner that while the piston is being propelled by the pressure produced by the combustion of a mixture of gas and air the air-pump draws in a charge of air and the gas-pump draws in a charge of gas during a variable part of its stroke, which latter charge during the return-stroke of the working-piston is compressed, while at the same time the charge 20 of air is first forced by the air-pump into the working-cylinder, assisting in the expulsion of the products of combustion, and then the compressed charge of gas is forced by the gas-pump, together with the air, into the working-cylinder, so that by the time the working-piston 25 has completed its instroke a chamber at the end of the cylinder is made to contain a compressed charge of combustible gas and air, which is richest in gas at the firing-port, and which is then fired, so that the engine makes a working- 30 stroke at each revolution of the crank-shaft, the engine-piston and the pistons of the air and gas pumps being all connected to one and the same crank, so as to make their strokes together. The power of the engine is regulated 35 by regulating the gas-supply to the gas-pump, this supply being entirely cut off when the normal speed of the engine is exceeded.

The accompanying drawings show a gas-engine constructed according to the above-described invention.

Figure 1 shows a sectional plan of the engine, the section through the slide being taken on the line *c d*, Figs. 3 and 3^a, while the section through the same parts at Fig. 1^a is taken

on line *a b*. Fig. 2 is a side view partly in section. Fig. 3 is an end view with the slide removed. Fig. 4 is a part plan showing the intermediate gas-valve in section. Fig. 3^a is a front view of the slide-valve. Figs. 5 and 6 are vertical sections taken, respectively, on lines *h i*, Fig. 3, and *e f g*, Fig. 1. Figs. 7, 8, and 9 show details of the cams; and Figs. 10 to 13 show diagrams of motion.

The piston of the working-cylinder 1 and the two coupled pistons of the air-pump cylinder 2 and of the gas-pump cylinder 3 are connected to the crank-shaft 4 by means of connecting-rods, the cranks being set in the same direction and parallel to one another, forming one common crank, as shown. The 60 working-cylinder 1 is generally similar in construction to that of the Otto engine—that is to say, it is of greater length than the stroke of the piston—so that when the piston is at the end of its instroke there is a space of material capacity between the latter and the back of the cylinder, which is to receive the compressed charge. In the air-pump and gas-pump cylinders no more than the unavoidable so-called “waste spaces” between pistons and cylinder ends are left at end stroke. The valve-shaft 5 receives its motion from the 65 crank-shaft in such a manner by gearing at 70 that it makes one revolution to one of the crank-shaft. The valve-shaft works the slide-valve 6 by means of a crank, 24, and the exhaust-valve 7 of the working-cylinder by means of the requisite intermediate parts of known construction, and likewise the ball-governor 8, which serves to regulate or to cut off the 75 admission of gas into the gas-cylinder 3 by means of a gas-valve, 9, acted on by a cam and suitable levers.

The mode of operation of this engine is as follows: When the working-piston is at the 80 end of its instroke, Fig. 1, the engine doing its normal work, the rear space in the working-cylinder 1 is filled with a compressed mixture of combustible gases or vapors and atmospheric air, and with a portion of the products of combustion which had not been expelled. Toward the end of the just-completed 85 stroke of the piston gas and air will have been

admitted simultaneously to the space of 1 through the inlet-passage 10 in such manner that when the piston attains the end of the instroke a richer explosive mixture is present in the passage 10 than there is in the charging-space of 1, in which the explosive mixture has been diluted by a surplus of air and a portion of the residual products of combustion. The ignition of the mixture compressed in the space of 1 is effected by a flame burning in a cavity, 22, of the slide 6. This flame, on being brought to the aperture of the passage 10, securely effects the ignition of the richer mixture contained in the passage 10. The pressure produced by the combustion of the charge causes the working-piston to perform its outstroke, during which work will be performed by expansion and transmitted to the fly-wheel shaft. During the same outstroke the piston of 2 draws atmospheric air into the air-pump cylinder through the passage 11, the cavity 21 in the slide 6, and through the pipe 12, which communicates with the surrounding atmosphere. The piston of the gas-cylinder 3, as a rule, draws in gas during a variable part of the stroke; or it may draw in no gas at all when no combustible charge is to be formed, in which case a partial vacuum will be produced in the gas-cylinder. The admission of the gas is controlled by a cam, 25, Fig. 8, acting on a bell-crank lever, 13, and causing it to open the gas-admission valve 9 at the commencement of the suction period. The gas from the valve 9 passes through the connection-pipe 14 and through the cavity 15 in the slide to the intermediate valve, 16, and this being held open during the suction period it passes on through the pipe 17 to the gas-pump. During this time the slide-valve 6 has been moving in the direction of the arrow, (see slide-valve diagram Fig. 10,) so that at the end of the suction period the slide has again attained the position shown on the drawings. The quantity of gas to be admitted can be varied at pleasure for the purpose of regulating the power of the engine by means of the oblique cam 25, (shown in Fig. 8,) which, by the action of the ball-governor 8, causes the gas-valve 9 to be held open either during the whole stroke or only a part of it, according to its relative position on the shaft, in a similar manner to the gas-admission cam of the Otto engine. When the pistons have attained the end of their outstroke, they commence simultaneously their return-stroke in the three cylinders under the following circumstances: The piston of the working-cylinder 1 expels the products of combustion, discharging them into the atmosphere through the exhaust-valve 7, which has been made to open for this purpose. At the same time the slide-valve 6, which at this moment is in the position shown in Fig. 1, begins to establish a communication between the air-cylinder 2 and the cylinder-space of 1 by means of the passage 11, the cavity 21 in the slide, and the passage 10. The atmospheric air previously drawn into the cylinder

2 is now forced into the cylinder 1 by the piston and assists in the expulsion of the residual products of combustion contained in the cylinder 1 and partly mixes with them. In the gas-cylinder 3 the gas will be compressed, if gas has previously been drawn in during the whole stroke, the intermediate valve, 16, being closed; but if gas has been drawn in during part of the outstroke only, the partial vacuum produced will be equalized and the work expended previously in producing a vacuum will be given out again. The exhaust-valve 7 of the working-cylinder 1 is made to close at about one-half of the stroke of the piston by means of a cam, 26, Fig. 9, on the valve-shaft and suitable levers. As soon as the exhaust-valve 7 has closed, the intermediate valve, 16, is opened by means of the cam 18, Fig. 7, and the bell-crank lever 19, Fig. 3, so that the gas from the gas-cylinder 3 may pass through the pipe 17 to the intermediate valve, 16, which has been opened, thence to the cavity 15 in the slide and to the passage 20 in the slide-cover, thence to the cavity 21 in the slide, and, finally, to the inlet-passage 10 of the working-cylinder, and into the cylinder itself. In this engine therefore by the action of the air and gas pumps first fresh air and afterward during the remaining part of the instroke gas together with air are admitted through the passage 10 into the compression-space 1. The mixture thus stored up in the passage 10 and cylinder-space 1 is thus compressed by the joint action of the three pistons until these have attained the end of their instroke. When the working-piston has arrived at the end of its instroke, ignition is effected, and the above-described cycle of operations begins again, so that in this engine an explosion takes place at every revolution of the crank-shaft. The operations in the three cylinders during one revolution of the crank are represented diagrammatically in Figs. 11, 12, and 13.

The above-described construction of engine embodies the following advantages, which are peculiar to it: It admits of an almost perfect expansion of the gases, which are at a high pressure after combustion, the degree of expansion depending on the ratio which the volume of the charging or compression space is made to bear to the volume swept through by the piston of the working-cylinder. Although the capacities of the gas and air pumps have to be in a suitable proportion to the capacity of the charging-space, yet, by varying the time when the exhaust-valve closes and the gas-valves open, the quantity and composition of the charge can be regulated at pleasure. The efficiency of this engine will therefore be of a very high degree.

The mode of regulating this engine by introducing more or less gas into the charge produces a very high degree of uniformity in the working of the engine. The ignition is rendered very secure, even with weak charges, in consequence of a strong explosive mixture

being always present in the inlet-passage. Moreover, in consequence of the air-pump forcing first pure air through the working-cylinder after the explosion and working-stroke have been effected, the cylinder is cooled and the residuary products of combustion are expelled, so that when the gas enters the cylinder no premature ignition can be caused.

Having thus described the nature of my invention and the best means I know for carrying the same into practical effect, I claim—

1. In a gas-motor engine, the combination of a single-acting working-cylinder with an air-pump and a gas-pump, the pistons of said air and gas pumps performing their strokes in time with the working-cylinder piston, the air-pump drawing in its charge during the working outstroke of the engine-piston and discharging its contents into the engine-cylinder during the entire instroke of the engine-piston, so as to assist in the expulsion of the products of combustion and allow the escape-valve to be closed at about one-half the instroke of the engine-piston, while the gas-pump draws in a variable charge during the outstroke of the engine-piston and forces that charge into the engine-cylinder after the closing of the escape-valve and while the charge of the engine-cylinder is being compressed by the completion of the instrokes of the engine-piston and air-pump piston, substantially as herein described.

2. In a gas-motor engine, the combination, with the working-cylinder 1, of an air-pump, 2, moving in time with the engine-piston and communicating with the cylinder 1 through passages 10 and 11 and cavity 21 of slide 6, making one to-and-fro motion for each revolution of the crank-shaft, the pump 2 drawing in a charge of air while the engine-piston performs its working outstroke and forcing that charge into the engine-cylinder through the slide-valve during the return-stroke, during the first part of which the products of combustion are expelled through an escape-valve, while during the last part the charge of air introduced is compressed, substantially as herein described.

3. In a gas-motor engine, the combination, with the engine-cylinder 1, of a gas-pump, 3, moving in time with the engine-piston and communicating with the gas-supply valve 9 through pipe 14, slide-cavity 15, valve 16, and pipe 17, and with the cylinder 1 through pipe 17, valve 16, and slide-cavity 15, the pump 3 being made to draw in a variable charge of combustible gas while the engine-piston performs its outstroke, then to compress the charge during the first part of the instroke of the engine-piston, and, lastly, to deliver the charge into the engine-cylinder during the last part of the piston's instroke, substantially as herein described.

4. In a gas-motor engine, the combination of a working-cylinder, 1, with inlet-port 10, an air-pump, 2, with passages 11 12, a gas-pump, 3, with passage 17 and valve 16, and a slide, 6, with cavities 15, 20, and 21, whereby charges of air and gas are drawn separately through the slide into the air and gas pumps, the charge of air being then delivered from the air-pump through the engine-slide into the engine-cylinder, after which the charge of gas is delivered in a compressed state from the gas-pump through the slide into the engine-cylinder, substantially as herein described.

5. In a gas-motor engine, a gas-pump receiving a charge of gas through a regulating-valve and delivering such charge into the cylinder through an intermediate valve actuated by a cam on the slide valve shaft, said intermediate valve being opened by the cam to allow the charge of gas to pass to the working-cylinder after the gas-pump has performed part of its stroke, substantially as and for the purposes herein described.

In testimony whereof I have signed my name to this specification, in presence of two subscribing witnesses, this 8th day of May, A. D. 1886.

NICOLAUS AUGUST OTTO.
